CLAIM

The ornamental design for an illuminated control device as
shown and described.

DESCRIPTION

FIG. 1 is a front perspective view of an illuminated control device showing a first state in a sequence showing our new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a front view showing a second state thereof;

FIG. 8 is a front view showing a third state thereof;

FIG. 9 is a front view showing a first state in a sequence comprising a second embodiment thereof;

FIG. 10 is a front view showing a second state thereof; and,
FIG. 11 is a front view showing a third state thereof.

The gray shaded elements depict illumination.

The dashed broken lines depict structure or features which
form no part of the claimed design; the broken lines them-
selves form no part of the claimed design.

In each of the embodiments, the claimed design sequentially
transitions from the first state to the last state in the
sequence. The period with which one image transitions to
another image forms no part of the claimed design.
